RECIPROCATING ENGINE

John George Aulsebrook Kitchen, Bowness-on-Windermere, Westmorland, England

Application September 25, 1936, Serial No. 102,616
In Great Britain December 5, 1935

2 Claims. (Cl. 121—1)

This invention relates to reciprocating engines. Its principal object is to provide an improved fluid-actuated engine in which frictional effects such as are inherent in ordinary reciprocating piston type engines are reduced to a minimum.

According to this invention, the working chamber of a reciprocating fluid-actuated engine comprises a series of at least three telescopically arranged non-contacting tubular elements whereof alternate elements are carried by two tube-carrying members which are relatively displaceable in the direction of the axis of the working chamber and which constitute a cylinder head and a piston head respectively. One of these heads has only one port therein arranged to permit a charge of working fluid under pressure to be admitted into the innermost tubular element of said series while the other head is devoid of ports. The tubular elements are of such length in relation to the stroke of the engine that some at least of the tubular elements carried by each head are always intercalated with those carried by the other head and all of the tubular elements are open at the ends opposite their heads so that the whole of each charge admitted through said port is compelled to traverse the sinuous path formed by the annular spaces between the tubular elements from the outermost of which spaces the exhaust issues at reduced pressure. Thus the charge of working fluid admitted to the innermost tubular element imparts driving energy to the piston head and expands through the whole series of tubular elements during one stroke of the piston head.

The tubular elements may be made of any metal and gauge suitable for the particular working fluid to be employed which may be steam, compressed air, products of combustion or other suitable fluid under pressure and it will be appreciated that as the fluid pressure on both the inner and outer faces of any of the tubular elements is substantially the same, there are no crushing strains to be allowed for and said elements can be much thinner than the cylinders of conventional reciprocating fluid-actuated engines of approximately the same power. For example, in the case of engines utilizing products of combustion, steel of about .022 inch gauge is suitable.

The accompanying drawings show as examples various ways in which the invention as applied to an engine may be carried out in practice. In the drawings:—

Figure 1 is an elevation partly in section of a simple form of a vertical single-acting engine; Figure 2 is a similar view showing a single-

acting engine according to the invention combined with a conventional piston engine of the two-stroke type;

Figure 3 is an elevation partly in section of a double-acting engine; 5

Figure 4 is a plan of same;

Figure 5 is a plan of a multiple working chamber engine;

Figure 6 is an elevation of same;

Figure 7 is a section on the line 7—7 of Figure 5;

Figure 8 is a section on the line 8—8 of Figure 5;

Figure 9 is an elevation partly in section of a radial engine; 15

Figure 10 is a plan of same;

Figure 11 is an elevation partly in section on the line 11—11 of Figure 10, and

Figure 12 is a detail view of the inlet valve casing of the radial engine. 20

The drawings are of a diagrammatic character, and like reference numerals indicate like parts throughout.

In the construction shown in Figure 1, there are two relatively axially displaceable tube-carrying members constituting a cylinder head 10 and a piston head 11 respectively. The head 10 is stationary and carries a number of concentric spaced tubular elements 12, and the head 11 is reciprocable and carries a number of concentric spaced tubular elements 13 which extend into the annular spaces between the tubular elements 12 without contacting therewith. All the tubular elements are of greater length than diameter and are open at their inner ends and the arrangement is such that a charge of working fluid supplied to the innermost tubular element 12 is caused to flow in a sinuous path between said elements. Thus the working fluid flows through the working chamber in a path of gradually increasing 40 cross-sectional area. The working fluid is supplied under pressure to the working chamber formed by the tubular elements 12, 13 through an inlet passage 14 in the cylinder head 10. This inlet passage is controlled by an inlet valve 15. 45 After flowing through the annular spaces between the tubular elements, the working fluid is exhausted to atmosphere at reduced pressure at the open end of the annular space between the outermost tubular elements 12 and 13. 50

The reciprocable piston head 11 is guided to avoid contact of the movable tubular elements 13 with the stationary tubular elements 12. In the construction shown in Figure 1, a rod 16 attached to the piston head 11 reaches through a 55

guide 17 in which it is free to slide endwise. Any convenient guiding means may be employed, but preferably means of the ball or roller type so as to reduce friction to a minimum. The rod 16 is connected by a connecting rod 18 to a crank 19 on a crank shaft 20 disposed below the working chamber of the engine. If it is desired to shorten the overall height of the engine, the crank shaft may be disposed at one side of the working chamber, any suitable operative connection being provided between the piston head 11 and the crank 19.

The inlet valve 15 may be operated by any suitable valve gear, for instance from a crank 15 or eccentric 21 on the crank shaft 20 through articulated valve-actuating rods 22.

It will be appreciated that this invention provides a reciprocating engine which is adapted to operate by a combination of impulse and reaction effects in a manner somewhat analogous to a reaction turbine, and that since the tubular elements forming the working chamber do not contact there will be a complete absence of friction in the working chamber and of any parts therein to which lubricant need be supplied. It follows, therefore, that if other parts of such an engine between which relative movement takes place are provided with ball or roller bearings, the friction will be reduced to a minimum and the attention required during running from the point of view of lubrication will be almost negligible.

The working chamber may comprise such a number of tubular elements that the exhaust will issue from the outermost tubular element at practically atmospheric pressure.

It will be appreciated that the provision of a relatively long path for the working fluid from inlet to exhaust enables the available energy in the fluid to be withdrawn therefrom before it reaches the exhaust outlet, and that the provision of sealing means between the relatively reciprocable tubular elements is unnecessary.

For the purpose of cooling the engine, or of obtaining maximum benefit from the expansion of the working fluid, water may be admitted to the innermost tubular element either with or after the admission of the working fluid, this water being afterwards separated from the exhausted working fluid and passed through a radiator for use again in the engine.

Figure 2 shows an arrangement in which an engine constructed according to this invention is combined with a conventional piston engine of the two-stroke type, the cylinder of which is indicated diagrammatically by the reference numeral 23. The piston 24 of this engine is connected by a connecting rod 25 to a crank 26 on the crank shaft 20, and a pipe 27 leads from the exhaust port of the cylinder 23 to the inlet passage 14 in the cylinder head 10. Thus the exhaust gases of the piston engine are utilized to operate the engine according to this invention and further expansion and reduction of pressure of the exhaust gases from the piston engine are obtained. In the arrangement shown in Figure 2, the exhaust from the working chamber is discharged into a casing 28 surrounding the tubular elements 12, 13, and an exhaust outlet 29 is provided from said casing. The casing 28 enables the exhaust to be collected, for instance, in the case of a steam engine for condensing purposes.

If desired, a casing such as 28 may be provided in the construction of Figure 1.

A double-acting engine according to the invention is shown in Figure 3. This engine comprises two stationary cylinder heads 10, whereof the sets of tubular elements 12 extend towards each other, and a common reciprocable piston head 11 which is disposed between the sets of tubular elements 12 and has on opposite sides sets of tubular elements 13 which are intercalated with the tubular elements 12. The piston head 11 is carried by an oscillatable arm 30 having at its lower end a pivot pin 31, and the tubular elements are curved to an arc having the axis of said pivot pin as a centre. The arm 30 oscillates in the casing 28 into which the exhaust from the working chambers is discharged, and the pivot pin 31 reaches through a laterally extending boss on the casing 28 and carries at its outer end an arm 32 which is connected by the connecting rod 18 to the crank 19 on the crank shaft 20. Mounted on the crank shaft are two cams or eccentrics 21 which through the valve gears 22 operate the inlet valves 15 in the cylinder heads 10 in properly timed relationship.

An engine according to this invention comparable with a conventional multi-cylinder internal combustion engine is shown in Figures 5 to 8 inclusive. This engine comprises two rows of working chambers 33, three in a row, which are spaced apart laterally. These working chambers are formed by the tubular elements 12, 13 but the cylinder heads 10 are in this case at the bottom and are fixed to a crank case 34. The piston heads 11 of corresponding working chambers in the two rows are rigidly connected by arms 35 to a guide cylinder 36 disposed between the working chambers. The guide cylinder is adapted to slide endwise over a hollow cylinder 37, see Figure 7, fixed to the crank case. Ball bearings 38 are provided between the cylinder 37 and the guide cylinder 36 to minimize friction. The guide cylinder is connected by the connecting rod 18 to the crank 19 on the crank shaft 20 which, it will be appreciated, is in this case a three-throw crank shaft having cranks set at 120° apart. The fuel is supplied by the aid of a blower 39 to two combustion heads 40 for serving respectively the two rows of working chambers 33. The combustion heads communicate with main fuel supply pipes 41 disposed one along each side of the crank case 34. Each of these supply pipes 40 communicates through branch pipes with three valve casings 42 each associated with one of the working chambers in the corresponding row. From each valve casing an inlet pipe 43 leads to the innermost tubular element 12 of the corresponding working chamber. The flow of fuel through the valve casing is controlled by the inlet valve 15, see Figure 8. The inlet valves for corresponding working chambers in the two rows are arranged to be opened by a double valve gear 44 controlled by a cam 45 on the crank shaft 20, there being three cams 45 set at 120° apart and three sets of valve gear as will be well understood.

The application of the invention to a radial engine is shown in Figures 9 to 12 inclusive. This engine comprises two sets of six working chambers 33 between which the guide cylinders 36 are arranged. The piston heads 11 are connected to the guide cylinders by the arms 35 as in the construction of Figures 5 to 8, and the guide cylinders are operatively connected by the connecting rods 18 to the single-throw crank shaft 20. Each of the fuel supply pipes 41 leading from the combustion heads (not shown) opens into an annular groove 46, see Figure 10, 75

in the valve casing 42 containing a rotary disc valve 47 fixed on the crank shaft 20. A through-way opening 48 in the disc valve is provided for establishing communication between the annular groove 46 and each of a number of ports 49 in turn leading to inlet passages 50 which communicate respectively with the innermost tubular elements 12 of the working chambers.

The invention is not restricted to the specific applications, nor to the constructional details shown on the accompanying drawings, as both of these may be varied within wide limits without departing from the invention.

I claim:

- 15 1. A reciprocating fluid-operated engine having a working chamber, comprising a series of at least three telescopically arranged non-contacting tubular elements whereof alternate elements are carried by two tube-carrying members which are relatively displaceable in the direction of the axis of the working chamber and which constitute a cylinder head and a piston head respectively, one of which heads has only one port therein arranged to permit a charge of working fluid 25 under pressure to be admitted into the innermost tubular element of said series while the other head is devoid of ports, which tubular elements are of such length in relation to the stroke of the engine that the tubular elements carried by each head are always intercalated with those carried by the other head and which are also open 30

at the ends opposite their heads so that the whole of each charge admitted through said port is compelled to traverse the sinuous path formed by the annular spaces between the tubular elements from the outermost of which spaces the exhaust issues at reduced pressure. 5

2. A reciprocating fluid-operated engine having a working chamber, comprising a series of at least three telescopically arranged non-contacting tubular elements whereof alternate elements are carried by two tube-carrying members, which are relatively displaceable in the direction of the axis of the working chamber and which constitute a cylinder head, and a piston head respectively, one of which heads has only one port therein arranged to permit a charge of working fluid under pressure to be admitted into the innermost tubular element of said series while the other head is devoid of ports, which tubular elements are open at the ends opposite their heads and are of such lengths in relation to the stroke of the engine that at least some of the tubular elements carried by each head will be intercalated throughout the stroke with those carried by the other head so as to provide in the working chamber a sinuous passage, formed by the annular spaces between the intercalated tubular elements, which has to be traversed by the whole of each charge admitted through the aforesaid port before it is exhausted from the working chamber. 10 15 20 25 30
